UNITED STATES PATENT OFFICE.

FRANK A. HOWARD, OF ELIZABETH, NEW JERSEY, ASSIGNOR TO STANDARD DEVELOPMENT COMPANY, A CORPORATION OF DELAWARE.

METHOD OF JOINTLY MANUFACTURING CARBURETED WATER GAS AND VOLATILE HYDROCARBON MOTOR FUELS.

Application filed March 24, 1921. Serial No. 455,200.

This invention is a method of jointly manufacturing carbureted water gas and volatile hydrocarbon motor fuels and will be fully understood from the following specification.

It is well known that relatively heavy hydrocarbon oils, such as petroleum distillates having a boiling point range of from 450° F. to 800° F., are well adapted for gas manufacture by cracking. This process is usually carried out in connection with the manufacture of blue gas or water gas, in which case the oil is vaporized and cracked in one part of a combination apparatus, another part of which is employed for furnishing the heat for the entire operation and for making the water gas by alternately serving as a gas producer and as a water gas generator. It is characteristic of this process that the cracking of the oil is carried on in an atmosphere of blue gas, that is, an atmosphere of which hydrogen represents about 50%, neglecting undecomposed steam.

In accordance with this invention, the peculiar conditions which obtain under these circumstances are controlled and utilized to effect a different species of cracking operation; that is, one which produces primarily liquid hydrocarbons of low boiling point together with greater or less quantities of permanent gas.

In the accompanying drawing a combination water gas generator and oil cracking apparatus suitable for carrying out the invention is shown in vertical section.

In the drawing the numeral 5 designates a generator, which is charged with fuel (coal, coke, and the like), through charging door 6, the fuel bed being indicated by numeral 7. Air for blasting is supplied through valved pipe 8. Steam may be supplied below the fuel bed through valved steam pipe 9 or above it through tuyères 10 supplied from valve controlled header 11. Valved gas outlets 12 and 13 from the generator 5 are provided above and below the fuel bed respectively, leading into the inlet pipe 14 to the carburetor 15. A valved pipe 16 for air also opens into the carburetor inlet pipe 14. The carburetor is provided internally with checkerwork 17. At its top is a spray pipe 18, which may be fed with oil through valved pipe 19, steam for atomization be-

ing introduced, if desired, through valved pipe 20.

From the carburetor 15 an outlet pipe 21 leads into the superheater 22. A valved pipe 23 for supplying air may be tapped into the pipe 21. The superheater is provided internally with a checkerwork 24. Its top is closed by valve 25, directly below stack 26. An outlet pipe 27 provided with valve 28 leads to the scrubber or condenser 29, into which a spray of water may be introduced through spray pipe 30. From the condenser 29 a liquid overflow pipe 31 leads into a separator 32 below the liquid level therein, and a valved gas pipe 33 leads from the condenser into the separator above the liquid level therein. The separator 32 is provided with a baffle or dam 33' extending below the liquid level in the separator. An overflow pipe 34 on the same side of the dam 33' as the inlet of pipe 31 serves to discharge from the separator floating oil and a second overflow pipe 35 on the other side of the dam serves to discharge water. A gas outlet pipe 36 opens into the separator. The ordinary type of tubular condenser and wash box may be used instead of the construction above described.

The operation of this apparatus is as follows: The generator 5 is blasted with air through pipe 8, the depth of the fuel bed being so great that the combustion gases are more or less rich in carbon monoxide. These gases pass in series through the checkered spaces of the carburetor 15 and superheater 22. Air may be admitted either between the generator 5 and carburetor 15 through pipes 16 or between the carburetor 15 and superheater 22 through pipe 23 or both as required to produce the requisite amount of combustion to raise the temperatures of the brick fillings 17 and 24 to the desired points. By varying the air blast to regulate the CO content, and by control of auxiliary air, the temperatures may be regulated through a very wide range. During this time the stack valve 25 is open and the valve 28 closed. When the fuel bed, carburetor and superheater have reached the operating temperatures, the air blast is shut off and valve 25 is closed and valve 28 opened. Steam is admitted either to top or bottom of the generator, passing up or down

as the case may be, to be decomposed with the liberation of hydrogen and the simultaneous production of carbon monoxide. The mixture of carbon monoxide, hydrogen and undecomposed steam passes from the generator 5 to the top of the carburetor 15, into which the heavy hydrocarbon oil is sprayed through pipe 18. The oil is vaporized almost instantaneously and the vapors carried by the high velocity current of mixed carbon monoxide and hydrogen pass through the heated checkerwork of the carburetor and superheater.

I have discovered that by a proper control of the temperature of the carburetor and superheater, and a proper correlation of these temperatures to the capacity or volume of the system and the rate of flow of the gases and vapors through it (these two last named conditions governing the time element of the cracking), the character and extent of the thermal decomposition of the oil may be controlled to produce a substantial yield of light hydrocarbons suitable for motor fuel. At the same time, the process of water gas manufacture and carburetion for which the apparatus is primarily designed, may be carried on without loss of efficiency or capacity, the production of motor fuel being made an incident of the regular operation of the carbureted water gas plant. In this way, the conversion of a certain proportion of the oil treated into permanent gas—which is an undesirable incident and an economic loss in an ordinary cracking process for producing motor fuel from heavy hydrocarbon oil—becomes an economically desirable feature. This modification of the water gas carbureting process to convert it into a combination carbureting and motor-fuel producing process is accomplished by greatly reducing the amount and extent of oil decomposition, which may be effected by lowering the temperature, by reducing the time element or both. For convenience and efficiency, as well as for the sake of obtaining a better quality of gas, both of these factors should be altered. For example, in a typical straight water gas carbureting process, the gas oil vapors are subjected to an average temperature of 1250° F. for a period of 4 seconds, giving a yield on the oil as follows:

	Per cent
55 Tar (heavy hydrocarbons)	15
Light hydrocarbons (practically all carried off in the fixed gases)	10
Fixed gases	75

60

100

If the time element were substantially cut, by cutting out the superheater, for example, or by reducing the percentage of voids through a change in the arrangement of the

checker brick, conditions remaining the same in other respects, the yield of fixed gas would be reduced and the yield of liquid hydrocarbons increased. Correspondingly, if the temperature of the carburetor and superheater were substantially reduced, all other conditions remaining the same, a similar result would be obtained. I prefer to adopt a combination of these methods, reducing both the temperature and the time. The temperatures in the carburetor and superheater may suitably be between 850° F. and 1050° F. At the same time, I prefer to use a relatively large quantity of gas oil with reference to the water gas produced, so that the total volume of fixed oil gas produced in each cycle of the apparatus is approximately the same as in normal water gas carbureting practice, and the thermal standard is properly maintained, say, between 450 and 650 B. t. u. per cubic foot. This is desirable in its effect of preserving the efficiency of the process as a producer of carbureted water gas, and also reacts favorably upon the time element, the increased volume of vapors and gas resulting from the introduction of the larger volume of oil increasing the means velocity through the heated checker brick and proportionately reducing the time during which any unit mass of oil is subjected to thermal decomposition. Furthermore, local overheating and excessive carbon deposits are avoided through the increased velocity and turbulence of the gas.

Under these conditions, the oil is decomposed without substantial liberation or deposition of carbon, yielding from 25% to 50% of low boiling point liquid hydrocarbons, consisting of a mixture of benzol, toluol and xylols, together with saturated and unsaturated aliphatic hydrocarbons boiling below 450° F. At the same time there is formed from 25% to 40% of heavier hydrocarbons, the balance of the oil being converted into permanent gas.

The oil supply is turned on shortly after the beginning of the water gas make and turned off before the end of the make period, in order to avoid waste of oil or oil gas through the stack valve. A typical process in accordance with the present invention is as follows:

Temperature fuel bed ----- 1850° F. 120
 Temperature carburetor ----- 875° F.
 Temperature superheater ----- 925° F.

Cycle.

Water gas make 3½ minutes, of which oil introduced 2½ minutes; blast and purge 5½ minutes; total cycle—9 minutes.

Cubic ft. water gas formed per minute—2500 for 3½ minutes.

125

Gallons of gas oil introduced per minute—
32 for $2\frac{1}{2}$ minutes.

Size of carburetor $8\frac{1}{2}'$ diameter, 13'
height, 50% voids.

5 Size of superheater $8\frac{1}{2}'$ diameter, $21\frac{1}{2}'$
height, 50% voids.

Products per cycle.

Gas oil introduced—80 gals. (32 gals. per
10 minute for $2\frac{1}{2}$ min.).

Total mixed gas produced—11,550 cu. ft.
of 560 B. t. u.

Total cracked oil produced—46.6 gals., of
which 24.4 gals. boils below 440° F. and
15 22.2 gals. above 440° F.

I claim:

The method of jointly manufacturing car-
bureted water gas and volatile hydrocar-
bon motor fuel which consists in air blast-
20 ing a bed of carbonaceous fuel to incan-
descence, passing the heated blast gases as
produced over heat absorbent material, to
heat the same to a temperature between 850°

F. and 1050° F., steam blasting the incan-
descence bed to produce water gas, passing the 25

heated water gas over the said heated mate-
rial, injecting into the current of heated wa-
ter gas a heavy hydrocarbon oil and thereby
causing the oil in vaporized form to pass

with the water gas over the said heated ma-
terial, controlling the rate of flow of the
30 mixed water gas and oil vapors, with ref-
erence to the temperature of the said heated

material, so as to secure a production of
fixed hydrocarbon gas not less than 15% 35

nor more than 60% of the weight of oil in-
jected, cooling the mixed gases and vapors to
cause condensation of the vaporous portion

thereof, separating the condensed oil includ-
ing volatile hydrocarbon motor fuel from 40
the fixed gases, and controlling the amount
of injected oil so that the said fixed gases
shall have an average B. t. u. value of not
less than 450 nor more than 650 per cubic
foot.

FRANK A. HOWARD.
